Attorney.

UNITED STATES PATENT OFFICE.

THOMAS B. MOORE, OF ROCHESTER, NEW YORK, ASSIGNOR OF ONE-HALF
TO GEORGE F. GALLAGHER, OF SAME PLACE.

FURNACE.

SPECIFICATION forming part of Letters Patent No. 393,258, dated November 20, 1888.

Application filed May 18, 1888. Serial No. 274,267. (No model.)

To all whom it may concern:

Be it known that I, THOMAS B. MOORE, a citizen of the United States, residing at Rochester, in the county of Monroe and State of New York, have invented certain new and useful Improvements in Furnaces; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates more particularly to that class of furnaces which have for their object the consumption of the products of combustion; and it consists in a certain improved construction, which I will now proceed to definitely describe and claim.

In the drawings, Figure 1 shows an elevation with one side sectioned to show interior construction, and Fig. 2 is a horizontal section through line *x x* of Fig. 1.

Referring to the drawings, *a* are the walls of the furnace, in which is seated the boiler *b*. *c* are the grate-bars, above which is the fire-box *d*, and below the ash-pit *e*. *f f* are the doors to the fire-box, and the ash-pit is provided with the usual doors, one of which is seen at *f'*, Fig. 1.

The parts thus far described are of ordinary and well-known construction, and to these I have applied my improved coking pockets or ovens as follows: *g g* are chambers or pockets arranged along the side walls of the fire-box from front to rear, access being had to the interior, for the admission of fuel, through the doors *g'* in the front wall of the furnace. Each pocket opens into the grate-bars along the lower and inner edge, as at *g''*, so that the coal which has been coked in the pockets *g*, which form ovens, can be pushed out into the grate-bars for further consumption. Between these pockets or ovens and the outer brick walls of the furnace are the chambers or passages *g''*, leading from the pockets *g*, and *g''* are passages opening into the chambers *g''* in the rear at *g''*.

(See Fig. 2.) These passages *g''* extend to the front wall of the fire-box, and thence along the front wall just over the grate-bars until they meet, as seen in Fig. 2, with their openings directed rearwardly.

Having now described the construction of my improved furnace, its operation is as follows: The pocket or oven—say on the right-hand side—is filled with coal through the door *g'*, the fire on the grate-bars between the pockets having been previously started. The coal in the pockets is gradually coked, the gases and other products passing down through chamber *g''* and passage *g''*, where they are discharged into the fire-box just over the grate-bars, and are there consumed before reaching the opening in the bridge-wall *h*. The fire in the open fire-box, which has been gradually burning out, is now replenished by pushing out the coked coal from the pocket through the opening *g''*. By employing the pockets on either side alternately, coked coal can be continuously furnished to the fire, while the gases and other products arising from the coal while it is being coked are conducted to the front of the fire, and in passing over the same are consumed, thus making practically a smokeless furnace.

The heat generated by my furnace could of course be utilized for other purposes than that of generating steam.

I claim—

A furnace for generating steam and for other purposes, consisting of ash-pit *e*, grate-bars *c*, fire-box *d*, and pockets or ovens *g* on either side of the fire-box, open at the bottom, as at *g''*, and connected from the top with the front of the fire-box by the chambers *g''* and passages *g''*, all operating substantially as and for the purpose stated.

In testimony whereof I have signed my name to this specification in the presence of two subscribing witnesses.

THOMAS B. MOORE.
